UNITED STATES PATENT OFFICE.

GILBERT J. DIETRICH, OF BEAUMONT, TEXAS.

PHONOGRAPH.

Application filed January 8, 1926. Serial No. 80,039.

This invention relates to phonographs, and has for its object to provide a drawer with a self-contained phonograph assembly, whereby the phonograph may be operated 5 from the front or face side of the drawer, without access from the top.

My object is to provide a phonograph assembly which may be placed in any piece of furniture, such as a dresser, writing desk 10 or library table, which has been designed with a drawer space to accommodate it; but most especially for the console cabinet with the solid top, so that the phonograph may be played without removing anything from 15 the top of the cabinet.

Another object of the invention is to provide a pivoted leaf which carries the turntable which is designed to be moved into or out of the drawer part, the parts being 20 so arranged that the phonograph can be played with the leaf in open or closed position or at any intermediate position.

This invention also consists in certain other features of construction and in the 25 combination and arrangement of the several parts, to be hereinafter fully described, illustrated in the accompanying drawings and specifically pointed out in the appended claims.

30 In describing my invention in detail, reference will be had to the accompanying drawings wherein like characters denote like or corresponding parts throughout the several views, and in which:—

35 Figure 1 is a plan view, with parts broken away, of the assembly with the leaf in open position.

Figure 2 is a section on line 2—2 of Figure 1.

40 Figure 3 is a section on line 3—3 of Figure 2.

Figure 4 is an enlarged detail view of the means for driving the turntable shaft from one of the horizontal shafts.

45 Figure 5 is an enlarged detail view showing the driving means adjacent the motor.

In these drawings, 1 indicates a drawer which is adapted to be placed in a recess formed in a piece of furniture, such as a console cabinet. A leaf or table 2 is pivotally connected at one corner to the front part of the drawer adjacent one edge thereof by means of the upper frame 3 and the lower frame 4. The upper frame has a pintle 3' 50 at its upper end which engages a hole

formed in a top piece of the drawer and the lower frame has its lower end rotatably connected with a stub shaft 5 vertically arranged on the bottom of the drawer, the shaft and pintle being in the same vertical 60 plane and these parts permit the leaf to be moved about a vertical axis so that it can be moved into the drawer or swung out of the drawer, this latter position being shown in Figure 1.

A horn box 6 arranged in the drawer and a horn tube 7 extends from the small rear end of said box to a point directly in line with the vertical axis of the table or leaf 2, where it is movably connected with the reproducer arm 8 in such a manner that the leaf or table 2 can move on its pivot without interference on the part of the arm and the tube and without moving these parts out of communication with each other, so that the 75 phonograph can be played with the table or leaf 2 in any position.

The motor 10 is also arranged in the drawer at the rear thereof and said motor may be wound up through means of the crank 80 handle 11, carried by one side of the drawer and which is connected by the sprockets and chain 12 to a shaft 13 which is connected with the shaft 11' of the motor to which the springs are attached by the gears 14 and the 85 ratchet mechanism 15. The motor drives a shaft 16 through means of the gears 17 and shafts 18 and said shaft 16 carries a gear 19 which engages a gear 20 rotatably mounted on the stub shaft 5 and this gear 20 is engaged by a gear 21 carried by a shaft 22 which is journaled in a collar 23, rotatably mounted on the shaft 5, and in a plate 24 carried by a frame 25 which depends from the leaf or table 2. Thus the gear 21 will remain in mesh with the gear 20 no matter in what position the table or leaf is moved into so that the shaft 22 will be driven from the motor at all times without regard to the position of the leaf or table 2. Shaft 22 is 90 connected by the gears 26 with a shaft 27 mounted in the frame 25, and the said shaft 27 is geared to the spindle or shaft 28 of the turntable 29 of the phonograph by the gears 30. The spindle is provided with the usual 100 governing means, shown generally at 31 and the stop parts shown generally at 32.

From the foregoing, it will be seen that the entire phonograph assembly is carried 105 by the drawer, and when this drawer is 110

placed in a cabinet, the phonograph can be played without raising the top of the cabinet. The pivoted support for the turntable enables a record to be placed on the turntable 5 or removed therefrom without reaching in the drawer, though while the record is being played, the turntable can be swung back into the drawer, if desired. Of course, it can be left projected from the drawer or it can 10 be placed in any intermediate position without interfering with the playing of the record.

While I have shown the shafts and gearing for communicating the movement of the 15 motor to the turntable, it will, of course, be understood that other means may be thus used, it being simply necessary to so arrange such means that they will not interfere with the movement of the leaf or table or prevent 20 playing of the record, with the leaf or table in any position.

It is thought from the foregoing description that the advantages and novel features of my invention will be readily apparent.

25 I desire it to be understood that I may make changes in the construction and in the combination and arrangement of the several parts, provided that such changes fall within the scope of the appended claim.

What I claim is:—

A phonograph comprising a drawer adapted to be placed in an article of furniture, the front of the drawer being open, a leaf, a pivoted frame extending upwardly from one corner of the leaf, a second pivoted frame depending from said corner of the leaf, a stub shaft in the drawer passing through the end of the depending frame and forming a pivot therefor, a pintle on the end of the top frame engaging a part of the drawer, said pintle and shaft being in vertical alignment, one of the corners of the drawer having a hole therein, the axis of which is in alignment with the pintle and shaft, a reproducer arm carried by the leaf and having a depending end rotatably arranged over the hole, a horn box in the drawer, a tube in communication with the box and having its outer end turned upwardly and communicating with the hole, a 45 motor in the drawer, a gear on the shaft, means for rotating the gear from the motor, a turntable on the leaf, means carried by the leaf for turning the turntable and means 50 for driving such means from the gear.

In testimony whereof I affix my signature.

GILBERT J. DIETRICH.
